VACUUM CLEANER BAG

Filed July 29, 1932

UNITED STATES PATENT OFFICE

CHARLES RALPH DICKINSON, OF GLENMOORE, PENNSYLVANIA

VACUUM CLEANER BAG

Application filed July 29, 1932. Serial No. 626,251.

This invention relates to the art of vacuum cleaners and more especially to an improved air and dust passage for vacuum cleaner dirt bags.

5 At present dust or dirt enter the lower end of the bag, and though the larger portion of the bag is suspended in a downward direction it is possible for the bag to clog or choke up as the bag tends toward filling, and thereby retard the entrance of subsequent dirt and dust.

With the idea of overcoming such contingency, it is the purpose of the present invention to provide an entrance passage for 15 substantially the full length of the bag, so that the dust and dirt may travel to the upper end of the bag and then deposit downwardly in the larger portion of the bag, and thereby prevent choking up and any back 20 pressure whatever in the bag.

While an entrance passage of this character can be employed in connection with cloth bags, it is the particular aim to use this invention (entrance passage) especially 25 for use in connection with paper bags, which are now being extensively used, because they can be thrown away, burnt up or otherwise destroyed, and thereby avoid the necessity of emptying the bag after once filled.

30 It is well known that there are certain vacuum cleaners, such as for instance in the patent to Paul Witte No. 1,802,228 which employ a permanent tube within the dust bag so that the dust and dirt can be carried 35 to the upper portion of the bag and deposited in the larger portion of the bag, thereby avoiding stoppage or any back pressure, but in this type of bag it is still necessary to empty the bag, and furthermore such 40 type of bag is not dispensable as with a paper bag, therefore it is not the aim of the present invention to claim broadly an entrance passage.

45 However the main purpose of the present invention is to convert the now extensively used paper bag, to provide for the same an entrance passage, by applying removable or detachable strips on opposite exterior faces of the paper bag, or even to a 50 cloth bag, thereby pinching together the op-

posite walls of the bag in order to form the entrance passage.

By providing such detachable or removable strips, it is obvious that the strips can be applied to the inexpensive paper bags at 55 the time of their manufacture, or the strips can be sold direct to the owners of vacuum cleaners, using paper bags, so that the strips can be applied to the bag by the owner.

A further purpose is to provide any suitable means for detachably or removably fastening the strips in position, or to employ a row of stitching, provided the strips are constructed of relatively heavy fiber or card board, to removably fasten the strips in 60 65 place.

While it is the purpose to use any improved detachable fastening means it is preferably the aim to employ the now extensively used conventional type of snap fastener, which comprises the male and female elements, the former being of such proportions as to pass through the walls of the paper bag and enter the female element, thereby not only separably fastening the 70 strips together and to the bag, but also clamping or pinching the opposite walls of the bags together, in such wise as to prevent any escape of the dust between the clamped or pinched parts but also causing the entrance 75 80 passage to be formed so as to carry the dust and dirt to the upper portion of the bag and deposit it in the larger part of the bag from the upper end thereof.

It is also the aim when using such type of snap fasteners to punch holes or perforations in the walls of the bag, in order to provide clean cut openings for the male element of the fastener.

It is also the aim to use the type of fastener 90 wherein the male element has a self-piercing sharpened thin flat blade like stud, which can force its way through the parts in order to engage the female element.

Also it is the aim to use a tubular clamp to 95 fasten the strips in place, or to use the tube without the strips.

The sole purpose of the invention is to provide a temporary clamping device for causing an entrance passage to be formed in a 100

vacuum cleaner dirt or dust bag, so that the temporary clamping means may be detached from one paper bag and applied to another.

It is to be understood that the particulars herein given are in no way limitative, and that while still keeping within the scope of the invention, any desired modification of details and proportions may be made in the construction of the appliance according to 10 circumstances.

The invention comprises further features and combination of parts to be hereinafter set forth, shown in the drawing and claimed:

In the drawing:—

15 Figure 1 is a view of a vacuum cleaner showing the dust or dirt bag provided with an entrance passage.

Figure 2 is a longitudinal sectional view through the same.

20 Figure 3 is a cross sectional view on line 3—3 of Figure 1.

Figure 4 is an enlarged sectional view on line 4—4 of Figure 2 showing one form of snap fastener.

25 Figure 5 is an enlarged sectional view showing a modified construction of snap fastener wherein the male element includes a self-piercing thin flat blade like stud which cuts its way through the walls of the bag.

30 Figure 6 is a view of another modified form, showing the strips clamped by means of a spring split tube.

Figure 7 is a perspective view of a dust bag, using a spring split tube to clamp the bag to 35 form the passage 7 without the clamping strips.

Figure 8 discloses enlarged views of the male and female elements of the fastener shown in Figure 5.

40 Figure 9 is a sectional view through a modified form showing bolts.

Referring to the drawing 1 identifies a vacuum cleaner of conventional type and 2 the dust or dirt bag, which is suspended in any 45 convenient way from the handle 3 of the vacuum cleaner.

Carried by the opposite walls of the bag, which is preferably constructed of paper, more or less porous for the passage of air therethrough, though it is obvious it may be constructed of cloth are clamping strips 4. These strips may be constructed of any suitable material, either wood, card board or similar fibrous material, and may be of any suitable length, thickness and width. These strips are disposed in position in alignment with one side of the restricted neck 5 of the bag, which is provided with a printed line 6 to indicate where the strips are to be applied, 50 thereby causing an entrance passage 7 to be formed. The strips terminate a short distance from the upper end of the bag to provide a throat 8 where the dust or dirt passes from the passage 7 into the larger portion of 65 the bag and therefore deposits at the bottom,

thereby preventing any stoppage or back pressure.

Carried by the strips 4 are snap fasteners 9, the male element 10 of which is carried by one strip, the female element 11 by the opposing strip, the strips being positioned on the opposite exterior surfaces of the walls of the bag incident to where the imprint line 6 is provided.

However before positioning the strips the 75 bag may be punched with openings or perforations 12 in order to provide openings with clean edges, so that the strips can closely contact with the opposite remote exterior surfaces of the walls of the bag, in order to insure 80 pinching or clamping the adjacent surfaces or the walls of the bag together, and in such wise as to prevent passage of dust or dirt between the adjacent parts, and also to insure the passage of the dust or dirt through the 85 throat 8.

Referring to Figure 5 it is to be noted that the male element of the fastener has a self-piercing thin flat blade like stud 13, which acts to cut its way through the material in 90 order to engage through the walls of the bag and into the female element. By this means there is no necessity of previously punching the openings or perforations in the walls of the bag in order to provide clean cutting 95 edges around the openings.

Referring to Figure 6 the strips are held in place by a spring split tube 14, which engages with grooves 15 formed in the remote faces of the strips, while in Figure 7 the 100 spring split tube is used to clamp the opposite walls of the bag without the use of the strips.

In Figure 6 the edges of the tube 14 engage into grooves 15 of the clamping strips, and 105 the adjacent faces of the clamping strips have sharpened points to penetrate the opposite walls of the bag. Arranged under the upper extremities of the clamping strips are circular or disc shaped shields 17, which are relatively large as shown, and they should possess a required amount of stiffness to protect the paper of the bag and prevent undue tearing or rupture to the walls of the bag, they also possess a reasonable amount of pliability to 110 permit them to yield in case the bag flexes more or less at its upper end.

The clamping strips 4 may be fastened together by small bolts and nuts 4a as shown in Figure 9, the bolts passing through the walls 115 of the paper bag.

The invention having been set forth, what is claimed is:

1. As an article of manufacture, a vacuum cleaner dust bag, comprising a bag body, a 125 pair of removable clamping elements disposed upon remote exterior opposite surfaces of the wall of the bag and in spaced parallel relation to one longitudinal edge of the bag, thereby causing an entrance passage to be 130

formed in the bag, and means for clamping the elements against the opposed surfaces of the bag.

2. As an article of manufacture, a vacuum cleaner dust bag comprising a bag body, a pair of clamping elements removably applied to remote opposite faces of the walls of the bag in spaced parallelism with one edge of the bag, thereby causing an entrance passage to be formed longitudinally of the bag and having a throat to discharge into the larger portion of the bag, and means carried by the elements penetratable through the walls of the bag for clamping the elements removably in position.

3. As an article of manufacture, a vacuum cleaner dust bag, comprising a bag body, a pair of clamping strips positioned on opposite remote faces of the bag in spaced parallelism to one edge of the bag thereby causing an entrance passage to be formed longitudinally of the bag terminating in a discharge throat at the upper end of the bag, and means carried by the strips penetratable through the walls of the bag for securing the strips in position.

4. As an article of manufacture, a vacuum cleaner dust bag, comprising a bag body, a pair of clamping strips positioned on opposite remote faces of the bag in spaced parallelism to one edge of the bag thereby causing an entrance passage to be formed longitudinally of the bag terminating in a discharge throat at the upper end of the bag, and snap fasteners carried by the strips comprising male and female elements, the male elements being penetratable through the walls of the bag to enter the female elements to fasten the strips removably in position.

40 5. As an article of manufacture, a pair of clamping strips to be positioned upon remote opposite faces of a vacuum cleaner dust bag, the strips to be disposed in spaced parallelism with one edge of the bag and having certain of their ends terminating a short distance from the upper end of the bag causing an entrance passage and a discharge throat to be formed, and snap fasteners carried by said strips, comprising male and female elements, the former being penetratable through the walls of the bag to engage the latter for detachably fastening the strips in place.

65 6. As an article of manufacture, a pair of clamping strips to be positioned upon remote opposite faces of a vacuum cleaner dust bag, the strips to be disposed in spaced parallelism with one edge of the bag and having certain of their ends terminating a short distance from the upper end of the bag causing an entrance passage and a discharge throat to be formed, and means carried by the strips and penetratable through the walls of the bag to removably fasten the strips in place.

In testimony whereof I affix my signature.

CHARLES RALPH DICKINSON.
